DUPLEX STRAINER UNIT

Russell G. Smith, Cincinnati, Ohio, assignor to Xomox
Corporation, Cincinnati, Ohio

Filed Sept. 8, 1970, Ser. No. 24,883

Term of patent 14 years

Int. Cl. D23—01

U.S. Cl. D23—4

FIG. 1

FIG. 1 is a front perspective view of a duplex strainer unit embodying my new design;

FIG. 2 is a rear elevational view thereof;

FIG. 3 is a side elevational view thereof;

FIG. 4 is a top plan view thereof; and

FIG. 5 is a bottom plan view thereof.

The drawing is a perspective view of a duplex strainer unit, embodying my new design.

I claim:

The ornamental design for a duplex strainer unit, as shown.
